UNITED STATES PATENT OFFICE.

CHARLES WALES, OF NEW HAVEN, CONNECTICUT, ASSIGNOR TO THE WHITE ADDING MACHINE COMPANY, OF NEW HAVEN, CONNECTICUT, A CORPORATION OF CONNECTICUT.

COMPUTING-MACHINE.

1,232,739.

Specification of Letters Patent. Patented July 10, 1917.

Application filed December 22, 1914. Serial No. 878,464.

To all whom it may concern:

Be it known that I, CHARLES WALES, a citizen of the United States, residing at New Haven, New Haven county, State of Connecticut, have invented certain new and useful Improvements in Computing-Machines, of which the following is a full, clear, and exact description.

My invention relates to improvements in computing machines and has for its object to provide a computing machine that encompasses many desired features in a machine of this character by the use of novel constructions and the fewest possible number of parts. By combining many offices in a single part much construction and waste of material is avoided. The simplicity of the parts and the possibility of their being manufactured out of easily obtained material, such as sheet steel, by use of tools of the character of punches and dies and the avoiding of bending parts after being punched, all tend to add durability and accuracy without lowering the grade of manufacture, also cheapen the cost. The entire absence of castings from the interior mechanism of the machine is a very strong feature for the reason that castings are expensive to make, hard to machine and inaccurate when machined in large numbers.

The following is a description of an embodiment of my invention, reference being had to the accompanying drawings in which—

35 Figure 1 shows a section of the machine on a plane just inside the right hand frames of the machine and keyboard.

Fig. 2 shows a section of the machine on a plane adjacent to the left hand frames of the machine, and certain other operative parts.

Fig. 3 shows a plan view of the numeral wheels and accumulating mechanism.

Fig. 4 shows a front elevation of the initial stops and sliding members on the rack bar carriers.

Fig. 5 shows a longitudinal section of a portion of the keyboard and a portion of the main frame of the machine, with parts for securing the early release of the numeral keys.

Fig. 6 shows a front view of the same parts on the line of the transverse break of Fig. 5.

55 Fig. 7 shows in full lines in side elevation

the motive portion of the machine in operative position and in dotted lines tipped forward so as to permit easy access to any part thereof for inspection and repair.

Referring more particularly to the drawings, 1 (Figs. 1 and 2) is the base of the machine and 2 is the cover which is secured to the base 1 by the hook 3 which engages with a stud 4 which is placed on the lower part of the cover. Panels of glass 5 and 6 are introduced in the front and sides of the machine and also in the top above the numeral wheels. The main frames 7 of the machine are secured to the base by a hinged connection, and in turn support the keyboard. Various transverse parts of the machine are held in their proper positions between side frames, (and this applies both to the main machine and the keyboard) in holes through which they project, and in some instances turn, much in the same manner as the works of a clock, it being possible to release and spring these frames so as to remove one part leaving others securely held in their original position. The keyboard consists of as many rows of numeral keys 10 as are desired, arranged side by side, each row consisting of nine keys placed at proper intervals and numbered from one to nine, the "one" key being nearest the operator and the "nine" key farthest away. These keys are retracted to normal position by springs surrounding their lower ends. Near the upper end of each of the keys 10, which are made to move in a perpendicular direction and stand in slots 11 in the key-board top 12, is a stud 13 (Figs. 1 and 6) which projects to the right into a recess in a pivotally mounted flexible shutter 14 and so arranged that when any key of its series is depressed the stud 13 passes below the lower edge of the flexible shutter so as to be engaged therein locking it in depressed position. Springs 15 connected to the cross-bar 16 hold the shutters in engaging position. One of the keys is shown in depressed position in Fig. 6. The lower ends of the keys are encircled by spiral springs 17 which return them to normal position. The lower ends of the keys are slidably held between bars 18 and angle irons 19 (Fig. 1) having slots cut in their edges. At the lower extremity of each key 10 is an ear 20 bent at an angle and pierced with a hole which surrounds the bent end of an index wire 21, which moves

in a horizontal plane through holes in angle irons 19 and plate 22 provided for its movement and support. The front ends of the index wires 21 are bent at an angle so as to provide a slanting portion 23 which passes through the hole in the ear 20 at the base of the key 10 and, being at an angle, as the key 10 is depressed the index wire 21 is thrust rearward. The index wires 21, eight in number for each series of keys, extend through the angle irons 19 and the plates 22, each one being beneath the other at given distances, their rear ends thrusting against an initial stop member 24 which has a shoulder 25, which under the action of the spring 24' normally lies beneath an indexing slide 26 and prevents motion of the rack-bar carrier 27 of the machine. Should any index wire 21 be thrust rearward it removes the corresponding initial stop 24 out of the path of the slide 26 and leaves the forward end of the rack-bar carrier 27 free to descend and stop upon such rearwardly moved index wire under the action of springs 27'. The rack-bar carrier 27 consists of a member loosely journaled on the central shaft 28 having three arms, one of which bears the slide 26 and is controlled by the index wires 21, another of which carries a vertically moving rack 29 and the third of which is connected through a link 30 with the type-bar 31 which carries the movable type 32. The indexing slide 26 provides a movable face for the first arm which is normally held in forward position by a spring 33. The purpose of this movable face is to permit the operator to set up a new item before a former item has been recorded and printed. Thus, should one of the index wires 21 be thrust rearward before a previous item has been recorded, it would come in contact with the indexing slide 26 of the rack-bar carrier, pushing it backward and carrying with it the corresponding initial stop 24. When the rack-bar carriers are thereafter restored to their normal positions the actuated index wire remains thrust rearward. The carriers are restored by the universal bar 27² carried by the cam plates 50, 50', which are at opposite sides of the machine and firmly fixed to the shaft 28. When the curved face of the indexing slide 26 passes by the end of the actuated index wire, the indexing slide moves back into its normal position and upon the succeeding movement of the rack-bar is stopped by the actuated index wire in the desired position for the new item to be added and printed. Each "nine" key 10' in the keyboard has but one office to perform, namely, it removes from the path of the rack-bar carrier 27 and its indexing slide 26 the initial stop 24, and the front end of the rack-bar carrier will continue its downward progress until it

reaches the bottom of the plate 22 in which the rear ends of the index wires 21 are held, the bottom edge of the plate 22 being bent at an angle of ninety degrees to limit its movement and constituting a limiting stop 22'. This key 10' acts upon a cam surface 34 on the initial stop 24. The rack-bar carriers 27 are strung side by side on the main shaft 28 of the machine and the middle or upwardly extending arm is provided with two ears 35 at the top, which are bent into a position parallel with the main shaft and are provided with milled slots. Sliding in these slots and having perpendicular motion is the rack-bar 29 provided with a section of teeth cut in its upper end, whose pitch line is concentric with the main shaft 28 when the rack 29 is in its elevated position and is in mesh with the corresponding numeral wheel pinion 36. The lower end of the rack-bar is provided with a slot 37 which surrounds a section of the hub 38 which carries the rack-bar carrier. This slot is of sufficient longitudinal length to permit the rack-bar to drop out of mesh with the pinion 36 and, when the rack-bar moves, to pass freely beneath the teeth of the pinion and not touch them, there being a series of pinions 36 constituting accumulating gears, and corresponding series of rack-bars 29 and carriers 27. For the purpose of elevating and lowering the rack-bars 29, their lower ends are each provided with a hook-shaped member 39, the inclosed space in which hook is in the nature of a curved slot 40 and concentric with the main shaft 28 of the machine when its rack-bar is in an elevated position. To give the rack-bars their proper motion a roller 41 (Figs. 1 and 2) is provided which rolls in the slot 40 at the lower end of the rack-bar, which roller is just about the size of the width of the slot, allowing but a little freedom of motion. It will be seen by this arrangement that no matter which one of the nine positions assumed by a rack-bar carrier, the roller when raised will raise its rack-bar and when the rack-bar carrier and rack-bar rotate, furnish a rolling bearing for the rack-bar. A series of rollers one for each rack-bar are strung upon a shaft 42 common to them all, which is thrust through the ends of a series of arms 43 centered on a shaft 44 at a point back of the main shaft and allowing the arms 43 to assume a horizontal position and so arranged that when the shaft 44 on which they are centered rotates they all rise at once and lift the rack-bars with them. At the left hand end of the shaft 44 on which the horizontal arms 43 are secured is an arm 45 depending in a vertical direction and having at its lower end a roller 46. Centered on a large shaft 47 in the rear of the machine, which shaft is in a position horizontal with the last named

roller and some distance behind it, is a loosely mounted secondary cam-plate or cam 48, having at its forward end a cam-slot 49 which surrounds the roller 46 on the end of the vertical arm 45 described above. The cam-slot 49 in the cam-plate 48 is of a width slightly larger than the roller 46 it incloses, and is formed having two surfaces concentric with the center on which the cam-plate revolves so as to form two dwells, the difference between these two surfaces being sufficient, when the cam-plate 48 operates, to cause the roller 46 to move in a circular path concentric with the shaft 44 on which the arm 45 is hung and to move a sufficient distance to turn said shaft and its various arms 43 and rollers 41 a sufficient distance to elevate the rack-bars 29 and cause them to come into mesh with the pinions 36. To facilitate the operation of these parts a gentle grade exists in the cam-slot 49 up which the roller 46 can roll with ease when operated. By this device it will be seen that any motion given to the cam 48 by whatever source in the machine, will move the rack-bars 29 no matter what position is assumed by the rack-bar or its rack-bar carriers. Mounted on the main shaft 28 of the machine are two irregularly shaped main cam plates 50, 50' having various cams and inclined planes for operating different parts of the machine. At the lower part of the main cam plate 50 is a stud 51 to which is connected a link 51^a whose other end is connected to the lever 51^b securely fixed to the shaft 47. A stud 51' on the cam plate 50' carries one end of a slotted link 52 which extends horizontally in a rearward direction and is perforated to inclose a stud 53 in the upper part of the cam 48 controlling the rack-bars, the slotted end delaying the action of the cam 48 and permitting it to rest after being pushed into a position placing the rack-bars 29 and the numeral wheel pinions 36 in mesh, and leaving it in that position until the machine has nearly returned to the normal position shown in the drawing. It is essential to hold this cam 48 in such a position until the other parts of the machine have nearly come to rest on the return stroke of the main handle, since the cam above described, being drawn by spring 60 toward the front of the machine would naturally follow the motions of the machine back into place were it not controlled. To hold it in nearly the position it takes in the forward stroke of the handle of the machine until the back stroke is almost finished is 60 a pawl 54, retracted by a spring 54' and centered on a center 55, and provided with a flat face or tooth 56 which drops into the path of a pin 57 set in the cam 48. The pawl 54 has an upwardly extending arm 58 lying at right angles to the slotted link 65

52 which operates the cam 48. A trip latch 58', carried by the stud 51' and riding at its other end on the link 52, is provided with a pin 59, which as the machine assumes the normal position shown in the drawings, strikes the upwardly extending arm 58 a lateral blow lifting its tooth 56 from in front of the stud 57 in the cam and releasing the cam 48 to the action of the spring 60 which turns it in an anti-clockwise direction. This system of control enables the rack-bars, when rotated clockwise by the universal bar, to turn the numeral wheels in an anti-clockwise direction and then drop out of mesh coincident with the return of parts of the machine to the normal position shown in the drawing.

It is necessary to protect an adding machine from a violent pulling of the handle which operates it or else the machine could be caused to move too fast for its various parts to perform their functions. To protect the machine from possible injury a flexible spring connection exists between the motive shaft 61 and the transmission shaft 47, so arranged that when the motive shaft 61 is violently moved the transmission shaft 47 will be drawn after it by springs at a slower rate. To control the action of the shaft 47 an ordinary dash-pot 62 (Fig. 2) is connected to a rearwardly extending arm 63 and so arranged that the oil in the dash-pot through its action on the piston will give the shaft 47 a uniform slow speed of operation. Mounted on the shaft 47 and firmly attached thereto are a pair of arms 64 (Fig. 1) having at their lower ends a rod 65 to which are attached a number of springs 66. On the shaft 61 are fixedly mounted similar arms 67 carrying a rod 68 for the reception of the springs 66 above mentioned. It will be seen that if the shaft 61 is rotated and the shaft 47 is held from rotation the springs 66 will be stretched and will continue so stretched until the parts on the shaft 47 controlled by the dash-pot follow at a slower speed under such control. It is necessary to limit the motion of the arms 64 on the shaft 47 in their motion after power has been transmitted through the springs 66, and for this purpose there is provided a connecting rod 69 extending from the rod 68 mounted on the shaft 61 to the lower end of a lever 70 hanging loosely upon the shaft 47, which connecting rod in turn comes in contact with the rod 65 mounted on the arms on the shaft 47 and maintains a distance between the rods to which the springs 66 are attached which cannot be less than the length of the rod 69. The shaft 61 is retracted to normal position by springs 66'. The rearwardly extending arm of the rack-bar mentioned above is connected to and operates portions of the printing section which are not a part in body of this

application and are described in my application No. 829,197, filed April 3, 1914.

In the top of the machine beneath the glass window 6 in the case and having two sets of numbers, "naught" to "nine", upon their periphery are the numeral wheels 71, each of which has mounted on it a pinion 36 having twenty teeth, one for each numeral wheel number, and a double-ended carrying pawl cam 72 (Figs. 2 and 3) having on each end a face 73 lying in a plane passing through the center of the numeral wheel and an inclined face 74, said faces so shaped that if the numeral wheel is revolved in a clockwise direction the face 73 of the double-ended pawl will catch on and stop against any interposed object and if revolved in an anti-clockwise direction the face 74 will give a camming motion to any interposed object. This arrangement is for the purpose of allowing the double-ended pawl cam 72 on the numeral wheel to operate certain carrying devices hereafter described while traveling in an anti-clockwise direction and also to retain the numeral wheels from more than half of a revolution in a clockwise direction. The numerals on the periphery of the numeral wheels are disposed in such a way that, when the double-ended pawl is in contact with a hereinafter mentioned part of the carrying device, a zero is placed at the peep hole 75 provided above the numeral wheel. The numeral wheels are contained in a housing consisting of two angle bars 76 (Fig. 3) which surround and are mortised to flat pieces 77 having at their ends holes through which is thrust a shaft 78 common to all the numeral wheels and forming stalls for the numeral wheels. Mounted on a shaft 79 at the lower corners of the stalls and almost in the angle of the lower angle bar are a set of carrying pawls 80, each one having an upright member carrying a forward cam-like projection which stands in the plane of the rotation of one of the double-ended pawls 72 on the numeral wheel and so arranged that when one end of the pawl 72 passes, it will force the carrying pawl 80 in a rearward direction. At the upper end of the carrying pawl is a small stud 81 extending laterally and carrying at its outward end a bolt 82 which extends between the flat pieces 77 and the numeral wheels and has its front end surrounded by a slot in an angle iron 83 extending across the machine. The front end of the bolt 82, when in its forward position, extends beneath a hooked end 84 on the carrying lever 85 and retains the carrying lever which is journaled in the shaft 78, carrying the numeral wheels, in an elevated position. It will be seen that if the bolt 82 is withdrawn the carrying lever, pulled by the spring 86, will rotate on the numeral wheel shaft until it falls upon a rod 87 extending clear across the machine and hav-

ing rollers 87 resting upon annular faces 88 of the main cam 50, which motion is approximately eighteen degrees or one-twentieth of a circle. Mounted upon the carrying lever 85 at a point about half-way its length is a combined lock and carrying pawl 89 consisting of a piece of metal the shape of a bell-crank. Its upper end is provided with a nose 90 which has the form of the interior part of a pinion tooth. Its horizontal member is connected to and operated by a link 91, which in turn is connected to and operated by the shaft 42 described above as lying at the lower end of the rack-bars and almost beneath the main shaft of the machine. The link 91 is provided at its lower end with an elongated vertical slot, which slot permits the shaft 42 to rise slightly before it picks up the link 91. It will be seen that by the use of this vertical slot that the rack-bar 29 will be slightly in mesh with the pinion 36 before the carrying-pawl 89 has started to move out of mesh, thereby locking the numeral wheel at all times. The same thing holds good in reverse order, when shaft 42 is traveling down. Attention is called to the unequal length of the arms of the carrying-pawl 89. This pawl is bell-crank in shape and the arm connected with link 91 is shorter than the upper arm which has the locking-nose 90 upon it. This produces the effect of moving the upper end faster than the end connected with the link 91. As the upward movement of the link 91 is practically coaxing with the movement of rack-bar 29, the quick retreat of the nose 90 is thus provided for. It will be seen by this arrangement that if the rack-bars of the machine are elevated and lowered as above described the carrying hooks 90 on the carrying-lever will be thrown into and out of mesh with the pinions on the numeral wheels according as the carrying-lever is in its elevated or lowered position. The upwardly extending arm of each carrying-lever 85 is provided at its forward side with a hook 92, (Figs. 1 and 3) the plane of which hook is slightly above the hook 84 on the opposite side of the upwardly extending member described above. This hook 92 is so arranged that it will stand above a rail 93, which operates on centers 93' in the main side frames of the machine when the hook 84 is in engagement with the bolt 82. This rail 93, when tipped back and under the hook 92, holds the carrying-lever 85 from motion after the bolts 82 have been withdrawn from the hooks 84. It will be seen by the arrangement of these two hooks 84 and 92, one above the other, that if the rail 93 is in position beneath the front hook 92, with the back hook 84 resting upon the end of the bolt 82, that if the bolt 82 is withdrawn the carrying lever 85 will move downward very slightly, but only a sufficient dis-

tance to keep the bolt 82 from returning and getting under the inner hook 84. At the end of the operation of adding, the rail 93 is thrown out from under the front hook 92 of the unbolted carrying lever 85, allowing it to descend and carry with it in rotation its pawl 90 and the corresponding numeral wheel. The carrying levers 85 have to be restored at the end of each addition to their normal positions and for this purpose the rod 87 described above, upon which they fall is provided with rollers 87' at each end and with arms 94 at each end which are centered on the shaft 78 carrying the numeral wheels. The rollers 87' at the end of the bar 87 carried by these arms 94 lie upon annular faces of the main cam 50 of the machine, which annular faces develop into cam faces 95 at a point approximating about two-thirds of the entire motion of the main cam 50. These cam faces 95 cause the bar 87 and its rollers 87' to mount up to a higher plane carrying with it the depressed carrying-levers 85 so as to restore them to bolted position. To be sure that the carrying-levers are fully hooked up on the bolts 82 the cam faces 95 on the main cam 50 of the machine are of sufficient height to slightly over-cock the carrying-levers so that the bolts 82 will be sure to assume their normal position beneath the hooks 84. The bolts 82 are controlled by suitable springs 96 to give them the forward motion necessary. If a bolt 82 and its carrying pawl 80 are connected together without the medium of a slot, it will be seen that on turning the numeral wheels to zero and allowing the double-ended pawls 72 on the numeral wheels to stand upon the carrying pawls 80 the carrying lever 85 in its upward motion and while latching with its bolt 82 would cam the bolt 82 backward and would carry the corresponding carrying-pawl 80 with it, removing it from the double-ended pawl on the numeral wheel and allowing the numeral wheel to turn farther back in a clockwise direction than zero. The bolt 82 where it engages the stud 81 of the pawl 80 is, therefore, slotted, one side being partially cut away to allow for easy assembly.

The rail 93, which retains the carrying-levers in their elevated position, to make the carrying operation successful must be removed from beneath the hooks 92 on the forward side of the upwardly extending arm on the carrying lever and allow them to drop, should the rail be tipped forward at the end of the motion of the whole adding mechanism. It would not be a fault if this action was delayed beyond the termination of the return movement of the rack-bars 29 so as to give the numeral wheels time to lose their inertia and come to rest, and to provide this, the rail 93 above referred to has an arm 97 extending backward and into

the machine, which is connected by a long link 98 to the cam 48 on the shaft 47 which, by means described above, controls the action of the rack-bars in their upward and downward movements. The lower end of this link 98 has a stud 99 (Fig. 1) which extends into a slot 100, open at one end and concentric with the center of the shaft 47. This slot 100 is of such length and shape that just as the cam 48 in which it is cut is coming to rest the stud 99 in the end of the slot 100 is thrust upward against the action of a suitable spring 101, and in turn forces the rail 93 out from under the carrying-levers 85 allowing them to drop and turn the numeral wheels. The interval occupied by the cam 48 on the shaft 47 in moving its entire distance is long enough to let the rack-bars 29 descend from mesh with the pinions on the numeral wheels and the carrying hook 90 on the carrying lever 85 to fully enter the teeth of the pinions 36 on the numeral wheels before the rail 93 is forced out from under the hooks 92 of the carrying levers. It will be seen that the fall of the carrying levers 85 will be delayed for a time after the other parts of the machine have gone to rest.

In the process of adding it is necessary at intervals to take what is known as a "sub-total", technically meaning printing what numbers are exposed upon the numeral wheels upon the strip of paper in the machine, and then causing the wheels to return to their former positions so that addition can be uninterruptedly continued. In taking a "total" it is desirable that the numeral wheels be returned to zero position and left there while the parts of the adding machine are restored to their normal position independently of the numeral wheels. It is also desirable that these two operations sub-totaling and totaling should be brought about by the use of separate keys on the key-board. It has been customary for the purpose of performing these two functions to provide separate internal means for each operation. I combine the means for performing these operations in one construction with the exception that two levers are provided extending from the key-board to the machine proper, both of which levers operate upon a mechanism common to them both, the only difference in their operation being the distance which they and the keys attached to them move. Centered in the side frames of the key-board section of the machine are the total lever 102 and sub-total lever 103, (Fig. 2) whose forward ends are depressed by keys 102' and 103' in the left hand side of the key-board. Their inner ends lie beneath a stud 104 in what is known as the totaling arm 105 and are so fulcrumed as to respectively give this stud 104 and its arm 105 two distinct movements.

Thus upon depressing the total key 102' the totaling arm 105 is raised to a nearly horizontal position. Upon depressing the sub-total key 103' it is raised to a point somewhat lower. If the operator should fail to fully depress either of these keys and pull the handle he would set up serious difficulty in the operation of the machine by such failure. To make it impossible for this to occur, I provide an L shaped piece 106 which is centered at 107 in the lower part of the left side frame of the machine. The upwardly extending arm of this member has three notches 108, 109, 110 with which the forward end of total-arm 105 engages. The member also has a forwardly extending arm 111 provided with a hook 112 which engages with and prevents the motion of a plate 113 having a sharp corner lying in the path of this hook, which plate is fixed to the shaft 61. The action of this plate 113, having a surface concentric with the shaft 61 is such that when it tips forward under the end of the hook 112, the hook and its upwardly extending arm are prevented from motion, and as the end of the totaling arm 105 is in one of the notches in its edge it cannot escape while the shaft 61 is moving. Likewise if the end of the totaling arm 105 is not in one of the notches but is opposite one of the higher surfaces of the upward arm the shaft 61 is locked from motion.

In order to retract the initial stops 25 when a sub-total is taken, I provide a lever 133 mounted on the left hand side frame of the keyboard (Fig. 2), the lower end of which lies in front of a universal bar 135 (Figs. 2, 5 and 6) carried by arms mounted on the shaft 127' and held in forward position by springs 24', acting through the initial stops to which they are connected. The upper end of the lever 133 is cam-shaped and is engaged by a pin 136 carried by the sub-total lever 103. When the sub-total lever is actuated, the pin 136 actuates the lever 133 so as to cause it to move the universal bar 135 to the rearward, carrying with it all of the initial stops 25, so as to be out of the way of the carriers. In order to retract the initial stops when a total is taken, I provide a somewhat similar lever 137 (Fig. 2), to the lower end of which is pivoted a hook 138 engaging the universal bar 135 and retracted by the spring 134. This lever 137 is actuated by a stud 139 on the total lever 102, so that when the total lever 102 is actuated the hook 138 draws the universal bar backward so as to retract the initial stops in a manner similar to their retraction when the sub-total lever is actuated. The hook 138 has its rearward end extending into the path of a pin 140 carried by a cam-plate 50' and is engaged by that pin when the cam-plate 50' is in its forward position, so as to be thereby

released from the universal bar 135. This permits the initial stops to move forward toward normal position, as soon as the total has been recorded, so as to bring the shoulers 25 beneath and in the path of the indexing slides 26, which are carried by the rack-bar carrier 27. This is a safety guard so that if the total-key be unduly held at its depressed position the rack-bar carriers and rack-bars will return to initial position.

In order to print an item for subsequent elimination, which item should not be added to the items already set up, I provide an elimination key 141 (Fig. 2) which acts upon a lever 142. When this key is actuated, the lever 142 engages the latch 54 so as to withdraw it from the path of the stud 57 with the result that an item set by the keys will be set up in the type 32, so as to be printed without being added to the items previously set up.

To make it impossible to confuse the operation of the total and sub-total keys by attempting to perform the function of one with the other two studs are set, one stud 114 in the upper arm of the hook and the other stud 115 in the end of the total lever 102 (Fig. 2), so arranged that they impinge one upon the other and while in such position prevent the notch normally occupied by said end when operated by the sub-total lever and key from engaging the end of the totaling arm 105, and also keep the hook 112 in engagement with the point of the plate 113.

To cause the numeral wheels to return to zero by turning them in a direction opposite to that employed in ordinary addition it is necessary to reverse the action of the whole adding machine in so far as its relationship to the numeral wheels is concerned. To bring this about the total arm 105 is provided with a downward extending link 116 pivoted at 117 (Fig. 2) and having at its lower end a slot 118 for a stud 119 carried by the cam 48. This arm carries a hook 120 pivoted thereto at 121, whose lower end under action of spring 116' engages the stud 119 on the cam 48 on the shaft 47 which cam controls the elevating and lowering of the rack-bars, thus bringing them into and out of engagement with the numeral wheel pinions. When the total key 102' is depressed this hook 120 lifts the cam 48 and in turn brings the rack-bars 29 into mesh with the pinions of the numeral wheels. The operator then pulling the handle under these conditions causes the numeral wheels to reverse and run backward from whatever number they may be standing at, to zero which positions the rack-bars for total printing. This is accomplished while the handle of the adding machine is moving forward toward the operator. As soon, however, as it starts backward in a direction away from the op-

erator it is necessary to withdraw the rack-bars 29 from the numeral wheel pinions 36 leaving the numeral wheels stationary while the machine is returning to its normal position, otherwise the numeral wheels would rotate to whatever position they formerly occupied. To do this it is necessary that the hook 120 engaging the stud of the cam 48 be removed from this stud allowing the cam 48 to drop and carry with it the rack-bars out of mesh with the numeral wheel pinions. To accomplish this the arm 116 is provided with a stud 122 which lifts the retention pawl 54 which controls the cam 48. It is, however, a fact that the mere removal of the pawl controlling the cam 48 will not allow it to operate for the reason that the hook 120 (Fig. 2) is and remains hooked on the stud 119 on the cam 48. To release the cam 48 from the hold of this hook 120 the latch 58; above referred to is provided with a notch 123. This trip latch notch 123, as the handle of the machine is about to start backward, engages with a stud 124 on the hook 120 and forces it to let go of the stud 119 on the cam 48 letting the cam 48 drop under the action of the spring 60, which carries the rack-bars downward and out of mesh with the pinions on the numeral wheels.

In taking a sub-total the depression of the sub-total key 103 lifts the total arm 105 (Fig. 2) to a position where its end engages with the notch 109 on the upward arm of the hook 106 and in so doing does not lift the arm 116 which is attached to the total arm 105 high enough to cause the stud 122 to release the pawl 54 from the pin 57 or bring the stud 124 into the path of the notch 123, said notch passing over the top of the stud 124 on the hook 120 without touching it. By this operation it will be seen that the action of the cam 48 is stopped in taking a sub-total and the rack-bars and the pinions on the numeral wheels remain in mesh and when the parts of the machine come to rest the numeral wheels are turned and restored to the positions they formerly occupied, leaving the addition to be continued as long as desired.

It has been customary to inclose the whole structure of an adding machine in side frames of cast iron or other material which extend practically the full length of the machine. This is a cumbersome and expensive arrangement and in my machine the key-board section and the motive portion of the machine itself are each contained in separate side frames made of sheet metal, making it possible to remove these two sections, one from the other for convenience in assembling and repairing. To make this possible the side frames of the key-board are provided with inwardly projecting studs 125 that are made to set in vertical notches 126 in the top and near the front of the

main side frames 7 of the motive portion of the machine. The lower rear corners of the side frames of the key-board are provided with a pair of hollow studs 127 made to swing into laterally extending slots 128 near the base of the front edge of the main side frames 7. It will be seen by this arrangement that the key-board can be raised as is the lid of a desk turning on the two studs 125 and it will also be seen that when it is dropped into its normal position it cannot be unhooked or disjointed from the main portion of the machine without being first raised so as to disengage the lower studs 127 from their slots 128. Then when so tipped by slightly lifting the key-board it will come free of the main portion of the machine. When the case 2 is in position, the key-board is prevented from tipping and is, therefore, firmly held in position. All the elements of the two parts, the key-board section and the main section of the machine are so disposed that they assume their normal relative positions without any adjustment whatever when the above operation of connecting them is performed, there being no nuts or screws to adjust, spring to hook up or any other connection whatever. This makes it possible to instantly remove and attach the key-board.

With the key-board removed from the machine it is desirable to give the repair or assembly man further access to all parts. Other machines have been provided with trap doors in their bottoms which can be taken off if necessary. To make all parts of the machine including the bottom instantly accessible to hands I provide a connection between the main side frames 7 and the base 1 which permits the use of hinged joints in the front corners of the side frames. On the base casting 1 of the machine are four lugs, 129, 130 the two forward ones 129 provided with screws 131 extending through them and into the forward corners of the side frame. The rearward lugs 130 are provided with holes through which is thrust a rod 132 extending clear across the machine and slightly beyond the faces of the side frame which rod is held from motion laterally when the case is in place on the machine. Upon withdrawing the rod 132, the motive portion of the machine can be tipped forward as shown in dots in Fig. 5, thus exposing the back of the machine in a horizontal position and the bottom of the motive portion in a vertical position, this being a great convenience. By my arrangement of centers and levers and members constituting various links and springs which are a medium of connection between the arms carried on the shafts 61 and 47 of the machine the shaft 47 can travel in an angle of approximately ninety degrees without straining any parts of the

- motive part of the machine or disarranging any of its mechanism. It is also possible with the key-board attached to the rest of the machine to tip the whole machine forward about twenty degrees without removing the keyboard which makes room enough for the operator's hands to be placed in the space at the back of the machine so created for the purpose of adjustment and repair.
- 10 Assuming that the machine, as shown in the drawings, is "cleared" so that the numeral wheels stand at zero, the operation is as follows: The keys 10 are first actuated, so as to position the stops 21 in the various series to correspond to the number which it is desired to set up. This not only positions the stops 21 but moves the initial stop 25 backward out of the path of the extension 26 of the carrier 27. After the number has been set up, the motive shaft 61 is moved counter-clockwise by the usual means which results in drawing the lever 64 forward and operating the shaft 47 in a clockwise direction. This moves the lever 51², which motion is communicated through the link 51^a to the main cam-plates 50 and 50'. These are thus turned in a counter-clockwise direction and the universal bar 22^a being lowered permits the carriers 27 corresponding to the initial stops 25 which may have been retracted to rotate counter-clockwise under the influence of their springs 27', until their movement is arrested by a stop 21. This positions the rack-bars 29 so that their positions correspond to the several numbers set up on the keys 10. During the latter part of the movement of the cam-plate 50', the pin 51', reaching the end of the slot in the link 52 which is connected to the cam 48, causes that cam 48 to rotate clockwise until the latch 54 falls beneath the projection 57, upon the cam 48. During this movement of the cam 48, the slot 49 acting upon the lever 45 causes the levers 43 to rise and lift the rack-bars 29 and to mesh with the teeth of the gear 36. It also, acting through the link 91, retracts the nose 90 of the alining and carrying-pawl so as to withdraw it from the teeth upon the gear 36.
- 45 The vertical elongation of the slots in the lower end of the links 91, through which the shaft 42 extends, permits the rack-bars 29 to begin their engagement with the gear teeth before the pawls 90 are withdrawn therefrom. Upon the return movement of the shaft 61 under the influence of the spring 66', the cam plates 50 and 50' are moved in a clockwise direction which results in a clockwise movement of the rack-bar carriers 27, while the rack bars 29 are still in engagement with the teeth of the gears 36. This moves the gears 36 counter-clockwise to an amount corresponding to whichever key 10 of its series was depressed. Just 60 prior to the end of the clockwise movement

of the cam-plates 50 and 50' the pin 59 engages the upright arm 58' of the latch 54, withdrawing it from the projection 57, so as to permit the cam 48 to move counter-clockwise under the influence of its spring 60, 70 which movement causes the cam-slot 49 to move the levers 43 so as to lower the rack-bars 29 and withdraw them from the teeth of the gears 36 and simultaneously causes the link 91 to move the pawl 90 so that its tooth enters between teeth upon said gear. In this way, the numeral wheels are moved a distance corresponding to the numbers set up upon the keys 10 and the parts, other than the numeral wheels and elements connected thereto, are restored to initial position.

The carrying operation is as follows: The face 74 of the cam 72, as it revolves counter-clockwise with the gear 36, engages the forwardly projecting nose on the pawl 80, which engagement is so timed as to force that pawl backward when the numeral wheels reach "zero" position. As the pawl 80 is forced backward, the bolt 82 is withdrawn from beneath the projection 84 of the carrying-lever 85 to the left. This permits the carrying-lever to fall until the nose 92 rests upon the upper edge of the retaining plate 93, the projection 84 being then in such a position that the bolt 82 cannot again move forward beneath it. This carrying-lever carries a pawl 90, which is in engagement with the teeth of the gear 36, which is to the left of the gear to which is connected the cam 72, which withdraws the bolt of that carrying-lever. After all the other parts of the machine except the cam 48 have come to rest and just before the cam 48 comes to rest after being released by the latch 54, the end of the slot 100 causes the pin 99 with its link 98 to move so as to cause the retaining plate 93 to move upon its center 93', with the result that the upper edge of the plate 93 moves forward so as to be withdrawn from beneath the projections 92. This permits the carrying-levers, supported by the plate 93, to be drawn downward by springs 86 until they rest against the shaft 87. At this time the pawls 90 of these carrying-levers are in engagement with their gears 36 and being carried by the carrying-levers 85, move their gears 36 through an arc of about 18° or one-twentieth of a revolution, thereby "carrying" from one 115 numeral wheel to the next. The carrying-levers are restored to their normal positions, so that the bolts 82 can come beneath their projections 84, by the universal bar 87, which is lifted upwardly by the inclined 125 cam surface 95 of the main cam during the period in which the rack-bar carriers are being positioned. The rearward arm of the carrier 27 acts through the link 30 to position the type-bars 32 properly relatively to 130

the platen (not shown), whereupon they are hit by suitable hammers, the mechanism for operating which does not form a part of the present invention.

5 The operation which takes place in printing totals and sub-totals has been fully described in connection with the description of the elements used for that purpose.

In order to insure a slight dwell before 10 the springs 66' retract the shaft 61, I provide a lever 142, loosely mounted on the shaft 47, and form in its hub a notch 143 with which the rear flat end of a distending member 144 engages when the shaft 61 is at 15 the end of its forward throw. The lever is engaged by a pawl 145 pivoted to the side frame at 146. 147 is a hammer mounted on the shaft 28 which, on the clockwise movement of the cam-plate 50, is cocked by 20 the stud 148 carried by the cam 50. 149 is a trigger which engages the hammer and holds it cocked. 150 is a pin that releases the trigger 149 when the cam-plate rotates counter-clockwise. The hammer, when released, is thrown by the spring 151. The action is as follows: If the shaft 61 is rotated counter-clockwise the end of the distender 144 engages the notch 143 and, except for the action of the hammer 147, would 30 remain there and hold the spring 66' distended. At the end of the counter-clockwise movement of the cam 50, however, the pin 150 trips the trigger 149 permitting the hammer to be thrown by its spring so as to 35 hit the upper end of the pawl 145, thereby releasing the lever 142 which, with its hub, turns so as to release the distender, whereupon the spring 66' contracts. This action results in a slight delay in the action of the 40 spring 66', insuring sufficient time for the carriers and other parts to be properly positioned. The stud 148 on the clockwise movement of the cam-plate 50 recocks the hammer so that it is restored to the position 45 shown in Fig. 1.

In order to secure an early release of the keys so as to permit the setting up of a new item before a previous item has been transferred to the numeral wheels and thus get 50 the full advantage of the slide 26 upon the rack bar carrier, I provide a transverse sliding plate 152 (Figs. 5 and 6) which has upward projections 153 engaging with the left hand edges of flexible shutters 14. This 55 sliding plate 152 is provided with an oblique slot 154, in which lies an anti-friction roller 155, mounted upon the end of a lever 156 pivoted at 157 in the right hand side-frame of the key-board. This lever is 60 provided at its rear end with a roller stud 158 (Fig. 5) which lies in the path of a yielding trip pawl 159 pivoted to the upper end of an arm 160 which is pivotally mounted at 161 on the side frame 7. The up- 65 wardly projecting arm 160 has a slot 162, in

which lies a stud 163 carried by the trip pawl, the stud being normally held in the rear end of said slot by the action of a spring 164 connected to the trip pawl and the upwardly extending arm. This trip pawl has a seat 165, which, when the trip pawl is moved forward, comes beneath the roller stud 158, and when the trip pawl is moved backward, raises the rear end of the lever 156, so as to depress the roller 155. 70 The spring 164 normally holds the trip pawl in the position shown but permits it to yield, so that its seat 165 readily passes beneath the roller stud 158 upon the lever 156, during forward movement of the trip pawl. The upwardly extending projection 167 upon the trip pawl prevents the trip pawl from snapping by the roller stud 158. When the trip pawl is moved in a rearward direction it acts to raise the rear end of 80 the lever 156 and to depress its forward end, whereupon the roller 155 causes the plate 152 to move to the right, causing the projections 153 to engage with the flexible shutters, move them to the right out of the path of the studs 13 upon the depressed keys, permitting the keys to return to normal position under the action of their springs 17. 85

In order to give the arm 160 (Fig. 5) the necessary movements to move the trip pawl backward and forward, I provide that arm with a roller stud 168 and form a slot 169 in the main cam 50 (Fig. 1), in which that roller stud moves and by which it is actuated. When the handle of the machine is 90 pulled so as to cause the cam 50 to move in a forward direction, the arm 160, together with the trip pawl 159 is also moved in a forward direction, until the seat 165 of the trip pawl comes beneath the roller stud 158 100 upon the lever 156. When the cam 50 moves in backward direction, the slot 169 acting upon the roller stud 168 causes the arm 160 together with the trip pawl 159 to move in a rearward direction and so that the trip pawl 110 actuates the lever 156 so as to release the keys in the manner above described. The backward movement of the cam 50, which results in this action, takes place shortly after the cam 50 begins its backward movement of rotation, so that the keys are released substantially as soon as the handle is released, this being permissible for the reason that the rack bars are, at that time, in engagement with the accumulating 115 gears. On account of the presence of the yielding faces 26 upon the rack bar carriers, a new item can, therefore, be set upon the keys substantially as soon as the handle is released. 120

This same lever 156 is operated whenever a total or sub-total key is depressed. In order to secure this, I provide a bell crank lever 170 pivoted to the right hand frame (Fig. 5) whose lower arm extends into the 130

pathway of an extension of the rod 135 which passes through slots 135' in the keyboard side frames. The other arm of this bell crank is connected by a link 171, to the 5 forward arm of the lever 156. As before described, whenever the total or sub-total key is depressed the rod 135 is moved backward as above described. This backward movement operates the bell crank 170 so as 10 to depress the lever 156 sufficiently to move the slide plate 152 enough to release any numeral keys which may be depressed.

As will be evident to those skilled in the art, my invention permits of various modifications without departing from the spirit 15 thereof or the scope of the appended claims.

What I claim is:

1. In a calculating machine, the combination of a keyboard, keys and stops therein, 20 the stops being actuated by said keys, a shaft, oscillating rack-bar carriers revolvably mounted on said shaft and coöperating with said stops, rack-bars carried by said carriers and movable toward and away from 25 the axis of revolution thereof, accumulating gears coöperating with said rack-bars, carrying mechanism for carrying from one of said gears to the next, a main cam-plate actuating said carriers, a secondary cam-plate 30 actuated by said main cam-plate, said secondary cam-plate acting to position said rack-bars and when actuated by said cam-plate to hold them in engagement with said gears, a detent for holding said secondary 35 cam-plate in actuated position, and means actuated by said main cam-plate for releasing said secondary cam-plate near the end of the return movement of said main cam-plate, a totalizing arm and means controlled 40 by said arm for preventing the holding action of said detent during substantially all of the return movement of said main cam-plate when said arm is in totalizing position.
2. In a calculating machine, the combination of a keyboard, keys and stops therein, 45 the stops being actuated by said keys, a shaft, oscillating rack-bar carriers revolvably mounted on said shaft and coöperating with said stops, rack-bars carried by said 50 carriers and movable toward and away from the axis of revolution thereof, accumulating gears coöperating with said rack-bars, carrying mechanism for carrying from one of said gears to the next, a main cam-plate actuating 55 said carriers, a secondary cam-plate actuated by said main cam-plate, said secondary cam-plate acting to position said rack-bars and when actuated by said cam-plate to hold them in engagement with said 60 gears, a detent for holding said secondary cam-plate in actuated position, and means actuated by said main cam-plate for releasing said secondary cam-plate near the end of the return movement of said main cam-plate, a totalizing arm and means 65 controlled by said arm for preventing the holding action of said detent during substantially all of the return movement of said main cam-plate when said arm is in totalizing position, total and sub-total levers for

controlled by said arm for preventing the holding action of said detent during substantially all of the return movement of said main cam-plate when said arm is in totalizing position, and total and sub-total levers 70 for placing said totalizing-arm in different positions.

3. In a calculating machine, the combination of a keyboard, keys and stops therein, the stops being actuated by said keys, a 75 shaft, oscillating rack-bar carriers revolvably mounted on said shaft and coöperating with said stops, rack-bars carried by said carriers and movable toward and away from the axis of revolution thereof, accumulating 80 gears coöperating with said rack-bars, carrying mechanism for carrying from one of said gears to the next, a main cam-plate actuating said carriers, a secondary cam-plate actuated by said main cam-plate, said secondary cam-plate acting to position said rack-bars and when actuated by said cam-plate to hold them in engagement with said gears, a detent for holding said secondary cam-plate in actuated position, and means 85 controlled by said arm for preventing the holding action of said detent during substantially all of the return movement of said main cam-plate, a totalizing arm and means 90 controlled by said arm for preventing the holding action of said detent during substantially all of the return movement of said main cam-plate when said arm is in totalizing position, and total and sub-total levers 95 for placing this totalizing-arm in different positions, and an interlock controlling the movements of said total-arm and said total and sub-total levers. 100

4. In a calculating machine, the combination of a keyboard, keys and stops thereon, the stops being actuated by said keys, a shaft, oscillating rack-bar carriers revolvably mounted on said shaft and coöperating with said stops, rack-bars carried by said carriers and movable toward and away from the axis of revolution thereof, accumulating 105 gears coöperating with said rack-bars, carrying mechanism for carrying from one of said gears to the next, a main cam-plate actuating said carriers, a secondary cam-plate actuated by said main cam-plate, said secondary cam-plate acting to position said rack-bars and when actuated by said cam-plate to hold them in engagement with said gears, a detent for holding said secondary cam-plate in actuated position, and means 110 actuated by said main cam-plate for releasing said secondary cam-plate near the end of the return movement of said main cam-plate, a totalizing-arm and means controlled by said arm for preventing the holding action of said detent during substantially all of the return movement of said main cam-plate when said arm is in totalizing 115 position, total and sub-total levers for 120

125

130

placing said totalizing-arm in different positions, and means preventing the operation of the machine when said totalizing-arm is held in sub-totalizing position by said total lever.

5. In a calculating machine, the combination of a main shaft, a main cam-plate thereon, a plurality of series of stops, a plurality of rack-bar carriers on said shaft, a plurality of radially movable rack-bars on said carriers, a plurality of gears, said carriers and rack-bars having a movement or oscillation about the axis of said shaft, said rack-bars having racks and curved slots concentric with said axis when said racks are positioned to engage said gears, bell-crank levers engaging said slots, said main cam-plate coacting with said stops to position and actuate said carriers, and a secondary cam-plate acting through said bell-crank levers to move said rack-bars radially into and out of engagement with said gears, means for oscillating said main cam-plate and a lost motion connection between said 25 cam-plates, and means for temporarily holding said secondary cam-plate in actuated position.

6. In a calculating machine, the combination of a main shaft, a main cam-plate thereon, a plurality of series of stops, a plurality of rack-bar carriers on said shaft, a plurality of radially movable rack-bars on said carriers, a plurality of gears, said carriers and rack-bars having a movement of oscillation about the axis of said shaft, said rack-bars having racks and curved slots concentric with said axis when said racks are positioned to engage said gears, bell-crank levers engaging said slots, said main cam-plate coacting with said stops to position and actuate said carriers, and a secondary cam-plate acting through said bell-crank levers to move said rack-bars radially into and out of engagement with said gears, means for oscillating said main cam-plate and a lost motion connection between said cam-plates, means for temporarily holding said secondary cam-plate in actuated position, a totalizing mechanism and means controlled by the totalizing mechanism for releasing said secondary cam-plate at the beginning of the return movement of said main cam-plate.

7. In a machine of the character described, the combination of a reciprocating actuator having a yielding abutment piece provided with an elongated face, a limiting stop, a series of movable normally retracted stops, each adapted to be projected into the normal path of said abutment piece, said series occupying a space less than that occupied by said elongated face and any of said movable stops engaging and retracting said abutment piece when actuated while said actuator is in one of its extreme positions

and in engagement with said limiting stop, said abutment piece returning to normal position when said actuator is returned to its other extreme position.

8. In a machine of the character described, the combination of a reciprocating actuator having a yielding abutment piece provided with an elongated face, a limiting stop, a series of movable normally retracted stops, each adapted to be projected into the normal path of said abutment piece, said series occupying a space less than that occupied by said elongated face and any of said movable stops engaging and retracting said abutment piece when actuated while said actuator is in one of its extreme positions and in engagement with said limiting stop, said abutment piece returning to normal position when said actuator is returned to its other extreme position, an initial stop engaging said abutment piece so as to hold said actuator in said other extreme position, any stop of said series being adapted when actuated to move said initial stop out of the normal path of said abutment piece.

9. In a machine of the character described, the combination of a reciprocating actuator having a yielding abutment piece provided with an elongated face, said abutment piece being moved by said actuator through a substantially vertical portion of a circle about the axis of said actuator, a limiting stop, a depending initial stop pivoted at its upper end and a series of movable normally retracted secondary stops each adapted to be projected into the normal path of said abutment piece and to retract the same when opposite thereto and to move said initial stop out of the normal path of said abutment piece said series occupying a space less than that occupied by said elongated face.

10. In a machine of the character described, the combination of a reciprocating actuator having a yielding abutment piece provided with an elongated face, a limiting stop, a series of movable normally retracted stop bars each adapted to be projected into the normal path of said abutment piece, said series occupying a space less than that occupied by said elongated face and any of said movable stop bars engaging and retracting said abutment piece when actuated while said actuator is in one of its extreme positions and in engagement with said limiting stop, said abutment piece returning to normal position when said actuator is returned to its other extreme position, and an initial stop engaging said abutment piece so as to hold said actuator in said other extreme position, any stop bar of said series being adapted when actuated to move said initial stop out of the normal path of said abutment piece, said abutment piece being slidingly mounted upon said actuator.

11. In a machine of the character described, the combination of a reciprocating actuator having a yielding abutment piece provided with an elongated face, a limiting stop, a series of movable normally retracted stop bars, each adapted to be projected into the normal path of said abutment piece, said series occupying a space less than that occupied by said elongated face and any of 5 said stop bars engaging and retracting said abutment piece when actuated while said actuator is in one of its extreme positions and in engagement with said limiting stop, said abutment piece returning to normal 10 position when said actuator is returned to initial position, an initial stop engaging said abutment piece so as to hold said actuator in initial position, any stop bar of said series being adapted when actuated to move 15 said initial stop out of the normal path of said abutment piece, said limiting stop being located below said series of stop bars. 20

12. In a calculating machine, the combination of a single totalizing-arm for setting 25 the machine for either totaling or sub-totalizing, two levers acting on said single arm, one for placing it in totalizing position and the other for placing it in sub-totalizing 30 position, and keys for operating said levers, radially movable rack-bars, a rack-bar controlling-cam, and means controlled by said totalizing-arm for releasing said cam in advance of its time for release in normal calculating operation. 35

13. In a calculating machine, the combination of a series of accumulating gears, a series 40 of combined alining and carrying-pawls therefor, and means for actuating each of said pawls to both aline said gears and carry from one gear to the next adjacent gear. 45

14. In a calculating machine, the combination of a series of gears, a series of combined 50 alining and carrying-pawls, levers to which said pawls are pivoted, means for selecting from said levers those which correspond to gears to which carrying is to be done, means for moving the selected levers while their pawls are in alining engagement with said gears and restoring them to position while 55 their pawls are disengaged from said gears each pawl being both an alining and a carrying pawl. 60

15. In a calculating machine, the combination of a series of gears, a series of pawls, a 65 series of carrying levers to which said pawls are pivoted, a series of bolts supporting said levers respectively, a series of dogs to which said bolts are connected at one end, and a cam on each gear for retracting the bolt controlling the lever which carries the pawl which engages the next adjacent gear. 70

16. In a calculating machine, the combination of a series of gears, a series of pawls, a 75 series of carrying levers to which said pawls are pivoted, a series of bolts supporting said

levers respectively, a series of dogs to which said bolts are connected at one end, and a cam on each gear for retracting the bolt controlling the lever which carries the pawl which engages the next adjacent gear, and a universal bar engaging and temporarily supporting in approximately their initial positions all of said levers whose bolts are retracted, and means for withdrawing said universal bar from beneath all of said levers. 75

17. In a calculating machine, the combination of a main cam-plate, a secondary cam-plate, lost motion connecting means between said cam-plates, oscillating rack-bar carriers released and returned by said main cam-plate, rack-bars on said carriers moved radially by said secondary cam-plate, a detent for holding said secondary cam in actuated position, means for releasing said detent near the end of the return movement 85 of said main cam, and means for angularly positioning said carriers. 80

18. In a calculating machine, the combination of a main cam-plate, a secondary cam-plate, lost motion connecting means between said cam-plates, oscillating rack-bar carriers released and returned by said main cam-plate, rack-bars on said carriers moved radially by said secondary cam-plate, a detent for holding said secondary arm in actuated position, means for releasing said detent near the end of the return movement of said main cam, and means for angularly positioning said carriers when moved into totalizing position for releasing said secondary cam-plate in advance of the time at which it would be released by the normal action of said main cam-plate. 100

19. In a calculating machine, the combination of a retracting spring, a distender, a lever having a retaining notch for said distender, an oscillating cam-plate, a hammer revoluble about the axis of said cam, a trigger for said hammer, a detent engaging said lever adapted to be hit by said hammer, means on said cam-plate for cocking said hammer, and means on said cam-plate for releasing said trigger so as to permit said hammer to hit said detent and withdraw it from said lever. 105

20. In a calculating machine, the combination of a series of rack-bar carriers, a series of rack-bars carried thereby, a series of initial stops, a plurality of series of secondary stops, each initial stop extending in front of all the stops of one of said series of secondary stops; each secondary stop of any series acting directly on the initial stop of that series to withdraw it from the path of the corresponding carrier, and keys for actuating said secondary stops, the releasing movement of the initial stop being in the opposite direction from the releasing movement of any secondary stop. 110

21. In a calculating machine, the combi- 115 120 125 130

nation of a series of rack-bar carriers, a series of rack-bars carried thereby, a series of initial stops, a plurality of series of secondary stops, each initial stop extending in front of all the stops of one of said series of secondary stops, each secondary stop of any series acting directly on the initial stop of that series to withdraw it from the path of the corresponding carrier, and keys for actuating said secondary stops, totalizing means and a bar directly engaging all of said initial stops and adapted to withdraw all of said initial stops from the paths of all of said carriers, said bar being actuated by said totalizing means, the releasing movement of the initial stop being in the opposite direction from the releasing movement of any secondary stop.

22. In a calculating machine, the combination of a series of rack-bar carriers, a series of rack-bars carried thereby, a series of initial stops, a plurality of series of secondary stops, each secondary stop of any series acting to withdraw the initial stop of that series from the path of the corresponding carrier, keys for actuating said secondary stops, and totalizing means adapted to withdraw all of said initial stops from the paths of all of said carriers, and means for releasing all of said initial stops before said totalizing means are restored to normal position when said totalizing means are held in totaling position.

23. In a calculating machine, the combination of a series of gears, two-faced cams carried thereby, carrying pawls, bolts controlling said pawls, dogs stopping said cams when said cams are revolved in one direction and together with said bolts retracted by said cams when said cams are revolved in the other direction, means for causing said pawls to carry when released, and means for restoring said pawls to initial position.

24. In a calculating machine, the combination of a base, a motive shaft thereon, a frame on the rear of said base, driven mechanism carried by said frame, a driving spring extending from a crank-arm on said motive shaft and connected near the rear of said frame to said driven mechanism, said frame being pivoted at its lower forward end to the central portion of said base and revolute through an angle upon said pivot.

25. In a calculating machine, the combination of a base, a motive shaft thereon, a frame on the rear of said base, driven mechanism carried by said frame, a driving spring extending from a crank-arm on said motive shaft and connected near the rear of said frame to said driven mechanism, said frame being pivoted at its lower forward end to the central portion of said base and revolute through an angle upon said pivot,

and movable means for securing the rear end of said frame to the rear end of said base.

26. In a calculating machine, the combination of a base, a frame on the rear end thereof containing the driven mechanism, a keyboard having keys and stops coöperating with said mechanism, said keyboard being removably suspended from the upper front portion of said frame.

27. In a calculating machine, the combination of a base, a frame on the rear end thereof containing the driven mechanism, a keyboard having keys and stops coöperating with said mechanism, said keyboard being removably suspended from the upper front portion of said frame, the points of suspension being in an axis about which the keyboard is partially revolute.

28. In a calculating machine, the combination of a base, a frame on the rear end thereof containing the driven mechanism, a keyboard having keys and stops coöperating with said mechanism, said keyboard being removably suspended from the upper front portion of said frame, the points of suspension being in an axis about which the keyboard is partially revolute, said keyboard and frame having engaging projections preventing the direct upward movement of said keyboard relatively to said frame.

29. In a calculating machine, the combination of a base, a frame on the rear end thereof containing the driven mechanism, a keyboard having keys and stops coöperating with said mechanism, said keyboard being removably suspended from the upper front portion of said frame, the points of suspension being in an axis about which the keyboard is partially revolute, said keyboard and frame having engaging projections preventing the direct upward movement of said keyboard relatively to said frame, a cover secured to said base and holding said keyboard against movement about said axis.

30. In a calculating machine, a frame containing the driven mechanism and forwardly extending movable members, a keyboard containing stops and rearwardly extending movable members coacting with said forwardly extending members, the ends of the coacting members being in different horizontal planes, said keyboard being supported by said frame and revolute about an axis lying within portions of both said frame and said keyboard and being unrestrained in such movement of revolution by said coacting members.

CHARLES WALES.
